STOKER CONSTRUCTION

William Thompson Hanna, Cincinnati, Ohio

Application June 9, 1930, Serial No. 459,996
Renewed October 29, 1936

9 Claims. (Cl. 83—52)

This invention relates to mechanical stokers but more particularly such as are adapted for use in locomotives.

One of the objects of the invention is to provide a simple and effective mechanism of this type which will withstand the exacting conditions of commercial use.

Further objects are to facilitate the repair or replacement of worn parts, to reduce the power consumption, to insure the free passage of the fuel in the hopper and conduits through which it passes from the tender to the fire box and to prevent fuel becoming wedged within the tender hopper. Other objects will be in part evident 15 and in part pointed out hereinafter.

The invention accordingly consists in the features of construction, combinations of elements, and arrangements of parts as will be exemplified in the structure to be hereinafter described and 20 the scope of the application of which will be indicated in the following claims.

In the accompanying drawings in which are shown the features of a selected embodiment of the invention:

25 Fig. 1 is a side elevation partially in section; Figs. 2 and 3 are enlarged detail sectional views;

Fig. 4 is a transverse sectional view substantially on the line 4—4 of Fig. 2, and

30 Figs. 5 and 6 are transverse sectional views on the lines 5—5 and 6—6 respectively of Fig. 3.

Referring to the drawings, there is shown a trough shaped tender hopper 10 into which the fuel falls by gravity through a suitable opening as 11 in the floor 12 of the tender 13. Within this 35 hopper and extending longitudinally thereof is a conveyor 14 of the spiral worm type. This conveyor 14 is connected at its forward end by means of a flexible joint to a conveyor 15 similar in construction thereto and operating within a conduit 16 leading to the fire box of the locomotive. The conduit 16 is connected at its rear end to an extension 17 of the hopper 10 by a flexible or ball and socket joint as 19 or other suitable means.

The forward end of the conduit 16 communicates with a housing 22 which receives the fuel delivered by the conveyor 15 and causes it to pass to the firing opening 23 of the fire box 24 of the locomotive. Below this housing is located a suitable power device as 25 which drives the conveyors 14 and 15 through the medium of shafting such as a telescopic shaft 26 and a gear (not shown) which meshes with a gear 27 keyed on a shaft 28 supported in a housing 29 having a bearing portion 30, such housing being secured to the rear 50 end of the tender hopper 10 and said shaft being

connected at its front end to the rear end of the conveyor 14. The construction of the housing 29 and the mechanism in the vicinity thereof is shown in detail in Figs. 2 and 4.

In order that the conveyor 14 may be quickly 5 and easily detached from the shaft 28, thus facilitating the removal and replacement of a worn out conveyor or the replacement of this shaft when necessary, a suitable form of coupling between this conveyor and the shaft may be provided.

As herein shown this coupling includes a socket member 31 secured in any suitable manner as by pin or rivet 33 to the rear end of the hub 32 of the conveyor, or it may be integral therewith. The rear portion of this socket member 31 fits over a flanged member as 34 and is rigidly but detachably secured thereto by bolts as 35 or in any other suitable manner. The member 34, as shown, is provided with a square hole 36 extending axially therethrough and 50 within this fits the square forward end 37 of the shaft 28 so that relative rotation of these parts is prevented. The member 34 may be secured endwise on this shaft in any suitable manner as by a dowel pin 38 extending therethrough and 55 held in position by socket 31 as shown in Fig. 4. The uncovering of this pin allows its withdrawal and the shaft 28 can be withdrawn through the rear end of the housing 29. On the reduced rear portion 39 of the shaft 28 is fitted the inner member 40 of a ball race thrust bearing 41, the outer member 42 of such bearing being fitted loosely within a recess 43 in the rear end of a cap plate 44 which is rigidly but detachably secured to the housing 29. The outer member 42 of this 60 ball race is held in position against movement axially of the shaft 28 by any suitable means such as a cap 42' which may be rigidly secured to the end of the cap 44. The rear end of the shaft 28 is threaded and a nut 45 thereon serves to secure 65 the inner member 40 of the thrust bearing on said shaft. This bearing serves to resist the end thrust of the conveyor 14 when such conveyor is rotated in either direction, but on account of the loose fit of the outer member 42 within the recess 70 43, the bearing does not support the shaft 28 annularly. The provision of this bearing which serves to resist the end thrust of the conveyor in either of the axial directions, has many advantages.

For example, in the actual operation of 50 such a stoker conveyor, as is above described, there may be an occasional clogging of the fuel in the conveyor. This clogging is readily broken by reversing the screw conveyor which permits the clearing of such an obstruction. In the present 55

construction, which is adapted to take the end thrust from either of the axial directions, the shaft is supported in a non-frictional manner, in whichever direction it is rotated.

5 As has been previously pointed out, the conveyor 14 and shaft 28 may be readily disconnected. This may be accomplished by merely removing the bolts 35. In this manner the conveyor 14 may be withdrawn forwardly from the 10 tender hopper and repaired or replaced as required, it being understood that the tender and the locomotive are disconnected at the time. The shaft 28 with gear 27 in place thereon may be removed from the housing 29 after the conveyor 15 has been disengaged in the manner described, by removing the cap plate 44 and drawing the shaft rearwardly from the bearing 30. The gear may then be easily removed from the shaft.

It will be observed that in the particular form 20 of the construction shown, the hub portion 32 of the conveyor 14 tapers in the direction in which the fuel advances and the conveyor is supported only at each end thereof, thus facilitating the free passage of the fuel throughout the 25 entire length of the tender hopper. Furthermore, in order that the operation of the conveying mechanism may not be interfered with by any extraneous matter becoming wedged between the periphery of the conveyor and the 30 wall of the tender hopper, I provide that the extent of the clearance space between the periphery of the conveyor and the wall of the hopper shall increase toward the delivery end of the conveyor. This is here accomplished by having 35 the bottom wall of the tender hopper arranged to increase in radius as it approaches the forward end of the hopper.

It is also desirable that means be provided for the ultimate removal from the hopper of any 40 such extraneous matter and to this end I have provided an opening in the bottom of the hopper which is normally closed as by means of a door 48 (Fig. 5), which in this instance is arranged to be hinged at 49 on projecting lugs 50 extending 45 from the wall of the hopper. Furthermore, I have provided that the door 48 may be opened and closed by means of a link pitman or reach rod 51 pivotally connected at 52 to an arm 53 extending from the door, the said reach rod 51 50 extending upwardly through and above the deck of the tender and provided with a handle portion 54 for convenient operation. It is also preferable to have the reach rod 51 arranged to be locked in its upward position in any suitable 55 manner as by means of a projection 55 which may be arranged to hook over the floor of the deck.

Referring to Fig. 5, it will be seen that the 60 inner surface of the door 48 is arranged to give an annular bearing support to the conveyor 14 at a point in line with the crushing device 56 which is secured within the tender hopper at its delivery end. Inasmuch as the greatest radial pressure on the conveyor occurs as a result of the 65 crushing operation, the annular bearing of the conveyor directly in line with the crushing device is subject to considerable wear and must from time to time be renewed. Thus it will be seen that having this door 48 form the support, 70 this heavy duty bearing may be cheaply and easily renewed when necessary.

It will be seen that there is provided a construction of an essentially practical nature in which the several objects of this invention are 75 attained.

As many possible embodiments may be made of the above invention without departing from the scope thereof, it is to be understood that all matter herein set forth or shown in the accompanying drawings is to be interpreted as illustrative and not in a limiting sense. 5

I claim:

1. In a locomotive stoker, in combination, a fuel hopper having a portion arranged in the form of a trough, a spiral conveyor mounted for rotation within said trough, a crushing device mounted within said trough adjacent the delivery end thereof and partially encompassing said conveyor, and a door hinged to open and close an opening in the bottom wall of said trough 15 adjacent the delivery end thereof and having its inner face arranged to provide bearing support for said conveyor.

2. In a stoker conveyer, in combination, a conveyer including a trough and a spiral conveyer 20 revolvably mounted within the said trough; and a thrust bearing located at the receiving end of said conveyer for receiving the end thrust of said spiral conveyer in either direction of rotation thereof, and a door in the bottom wall of 25 said trough adjacent the delivery end thereof for providing bearing support for the outer periphery of said spiral conveyer.

3. In a stoker conveyer, in combination, a conveyer including a trough and a spiral conveyer 30 revolvably mounted within the said trough; and a thrust bearing located at the receiving end of said conveyer for receiving the end thrust of said spiral conveyer in either direction of rotation thereof, a door in the bottom wall of said trough adjacent 35 the delivery end thereof for providing bearing support for the outer periphery of said spiral conveyer, and manually operable means for conveniently opening and closing said door, said means being located above the floor of said tender. 40

4. In a locomotive stoker in combination, a fuel hopper having a portion in the form of a trough to receive fuel, a screw conveyer mounted within said trough and extending longitudinally thereof, the wall of said trough being arranged with reference 45 to the periphery of said conveyer to provide increasing clearance space therebetween which progressively increases toward the discharge end of said trough without materially adversely affecting the fuel moving capacity of said conveyer, a crusher associated with said hopper at the delivery end for crushing fuel moved therewith by said screw conveyer and a retractable bearing support 50 for the outer periphery of said conveyer below said conveyer and crusher for supporting said conveyer 55 against the thrust caused by said crusher, said supporting means being retractable to free foreign material moving down the trough to the supporting means.

5. Fuel feeding apparatus comprising a trough-shaped hopper having a discharge opening and an opening in its bottom wall adjacent said discharge opening, a spiral conveyer rotatably mounted in said hopper to advance fuel therethrough toward said discharge opening and including an axial 65 shaft and a helical vane, a bearing removed from said discharge opening for supporting one end of said shaft, and a bearing member supported outside said hopper and arranged to be moved inwardly through said opening in the hopper wall to 70 engage and provide a bearing for a peripheral portion of said helical vane, and outwardly to relieve clogging of fuel in the hopper, the interior cross-sectional area of the hopper increasing progressively in the direction of the discharge open- 75

ing to increase correspondingly the clearance between said helical vane and the fuel supporting surface of said hopper.

6. Fuel feeding apparatus comprising a trough-shaped hopper having a discharge opening and an opening in its bottom wall adjacent said discharge opening, a spiral conveyer rotatably mounted in said hopper to advance fuel therethrough toward said discharge opening and including an axial shaft and a helical vane, a bearing removed from said discharge opening for supporting one end of said shaft, and a bearing member supported outside said hopper and arranged to be moved inwardly through said opening in the hopper wall to engage and provide a bearing for a peripheral portion of said helical vane, and outwardly to relieve clogging of fuel in the hopper, the interior cross-sectional area of the hopper increasing progressively in the direction of the discharge opening to increase correspondingly the clearance between said vane and the fuel supporting surface of said hopper and the cross-sectional area of the axial shaft decreasing in the same direction.

7. In a locomotive stoker, in combination, a fuel hopper having a portion in the form of a trough having a discharge end, a rotary screw conveyer mounted within said trough and extending longitudinally thereof, a crushing device within said trough adjacent said discharge end, mounting means for mounting said rotary screw conveyer within said trough and for providing clearance space between the bottom wall of said trough and the loci of all the fuel contacting parts of said screw conveyer, said clearance space progressively increasing toward the discharge end of said trough.

8. In a crushing and feeding mechanism, located below a floor of a locomotive tender, in combination, a hopper, and a screw conveyer mounted in said hopper; a crushing device mounted within said hopper and co-acting with said screw conveyer to crush fuel forced thereagainst by said screw conveyer; and a door in the bottom wall of said hopper, having its inner face projecting inwardly beyond the normal interior surface thereof and opposite portions of said crushing device whereby in the event of clogging of fuel within the region of said crushing device said door may be opened to relieve the clogging and the pressure created by said clogging; and manually operable means having a portion extending through the floor of the tender for conveniently opening and closing said door.

9. In a crushing and feeding mechanism, located beneath the floor of a locomotive tender, in combination, a hopper, a screw conveyer rotatably mounted adjacent the floor of said hopper, a crushing device mounted within said hopper and co-acting with said screw conveyer to crush fuel forced thereagainst by said screw conveyer, a door hinged to open and close an opening in the floor of said trough approximately beneath said crushing device, manually operable means for readily closing and latching said door constructed to afford mechanical advantage to multiply the effect of manual force exerted to close the door, said means being quickly releasable to open said door about its hinges, and a handle portion extending from said manually operable means for manipulating said means, said handle portion being conveniently located for manual manipulation.

WILLIAM THOMPSON HANNA.
